UNITED STATES PATENT OFFICE.

BERNARD P. WAGNER, OF SIDNEY, OHIO.

DESIGN FOR A VESSEL.

SPECIFICATION forming part of Design No: 35,759, dated February 18, 1902.

Application filed December 31, 1901. Serial No. 87,974. Term of patent 14 years.

To all whom it may concern:

Be it known that I, BERNARD P. WAGNER, a citizen of the United States, residing at Sidney, in the county of Shelby and State of Ohio, have invented and produced a new and original Design for Vessels, of which the following is a specification, reference being had to the accompanying drawings, forming part thereof.

Figure 1 is a side elevation of a vessel, showing my new design. Fig. 2 is an end view of the vessel, showing my design. Fig. 3 is a sectional view taken on line 2 2 of Fig. 4. Fig. 4 is a sectional view taken on line 3 3 of Fig. 1.

As shown in the drawings, the leading or material feature of my design consists of a series of exterior faces 1, said faces each having its main central portion 2 in a right plane and its upper part 3 terminating in a rounded surface at the upper part of the vessel, said faces at their lower ends being curved

inwardly at 4 and terminating in a curved surface 5, these faces and surfaces being arranged and associated on the outer surface of 25 a vessel, as shown.

6 denotes cheeks adjacent the vessel-nose 7, which has approximately plain faces 8, continuous with the cheeks and with a lengthwise-curved face 9 and with curved faces 10 30 and 11, which latter faces disappear in the curved surface 5, as indicated in the drawings.

Having described my invention, what I claim as new, and desire to secure by Letters Patent, is—

The design for a vessel, as herein shown and described.

In testimony whereof I have signed my name to this specification in the presence of two subscribing witnesses.

BERNARD P. WAGNER.
